(57) **CLAIM**

The ornamental design for a plug for a beverage lid, as shown and described.

DESCRIPTION

FIG. 1 is a perspective view of embodiment one of a plug for a beverage lid, showing my new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is a perspective view of embodiment two of a plug for a beverage lid, showing my new design.

The broken lines shown represent portions of a plug for a beverage lid and form no part of the claimed design.

The plug for a beverage lid has been shown with symbolic breaks. The appearance of any portion of the article between the break lines in FIGS. 1-3 and 6-8 forms no part of the claimed design.
